US00D935018S

(12) **United States Design Patent** (10) **Patent No.:** **US D935,018 S**
(45) **Date of Patent:** **** Nov. 2, 2021**

(54) **CONTRACEPTIVE**

(71) Applicant: **The Population Council, Inc.**, New York, NY (US)

(72) Inventor: **Bruce Variano**, White Plains, NY (US)

(73) Assignee: **The Population Council, Inc.**, New York, NY (US)

(**) Term: **15 Years**

(21) Appl. No.: **29/730,703**

(22) Filed: **Apr. 7, 2020**

(51) LOC (13) Cl. **24-02**

(52) U.S. Cl.

USPC **D24/141**

(58) **Field of Classification Search**

USPC D24/141, 105, 107, 143

CPC A61F 6/00; A61F 6/08; A61F 6/14; A61F 2/005; A61F 2/0027; A61F 2/0036

See application file for complete search history.

(57) **CLAIM**

The ornamental design for a contraceptive, as shown and described.

DESCRIPTION

FIG. 1 is a perspective view of a contraceptive showing the claimed design;

FIG. 2 is a top view thereof, the bottom view being the same;

FIG. 3 is a side view thereof;

FIG. 4 is another side view thereof;

FIG. 5 is another side view thereof, the opposite side view being a mirror image thereof; and,

FIG. 6 is a cross-sectional view thereof, taken along line 6-6 of FIG. 5.

1 Claim, 5 Drawing Sheets
